UNITED STATES PATENT OFFICE.

CHARLES H. JARVIS, OF BATTLE CREEK, MICHIGAN, ASSIGNOR TO UNITED STEEL AND WIRE CO., OF BATTLE CREEK, MICHIGAN.

DISPLAY STAND.

Application filed October 7, 1922. Serial No. 593,132.

To all whom it may concern:

Be it known that I, CHARLES H. JARVIS, a citizen of the United States, residing at Battle Creek, county of Calhoun, State of Michigan, have invented certain new and useful Improvements in Display Stands, of which the following is a specification.

This invention relates to improvements in display stands.

10 The main object of this invention is to provide an improved display stand for flowers and other objects in pots or receptacles, the articles being effectively supported for display and comparison.

15 A further object is to provide an improved display stand which is attractive in appearance and strong and rigid, although made of light materials.

Further objects, and objects pertaining to 20 details and economies of the invention will definitely appear from the detailed description to follow.

I accomplish the objects of my invention by the devices and means described in the 25 following specification. The invention is clearly defined and pointed out in the claims.

A structure which is a preferred embodiment of the invention is clearly illustrated 30 in the accompanying drawing forming a part of this application, in which:

Fig. I is a perspective view of my display stand.

Fig. II is a side elevation thereof with 35 flower pots arranged therein, a portion of the upper flower pot being broken away for convenience in illustration.

In the drawing similar reference characters refer to similar parts in both views.

40 My improved flower stand in the preferred embodiment illustrated has legs 1 with angular bends 2 at the upper ends thereof, the legs being disposed in triangular relation with their angles 2 inwardly. 45 This provides a flaring effect for the top of the stand.

The annular top member 3 is welded to the upper ends of the legs and is provided with cross bars 4 and 5 which provide a top 50 or support on which an article such as the flower pot 6 may be arranged in upright position as desired, or may be disposed in an inclined position with its side resting

against one of the cross pieces 4 and its bottom against the other as shown in Fig. II. 55

I also provide triangular horizontal members 7 which are secured in the angles thereof to the legs as by spot welding. A horizontal member 8 is disposed near the angles of the legs. Cross pieces 9 are secured to the horizontal members 7 in spaced relation to one of the side members thereof and coacting therewith to support the receptacles 6, such as flower pots, with their bottoms resting against the cross pieces and 60 their sides against the adjacent side member. 65

My improved stand provides for the arrangement of several articles, such as pots or flowers, for display purposes, or for the 70 use of undertakers, a pyramid effect being possible, particularly where a plurality of stands are used. The stand may also be used for supporting receptacles containing various kinds of merchandise. I have illustrated 75 my improvements in the form in which I have embodied them for the display of flowers.

Having thus described my invention what I claim as new and desire to secure by Letters Patent is:

1. In a stand, the combination of legs having angular bends adjacent their upper ends disposed in triangular relation with their angles inwardly, an annular top member 85 welded to the upper ends of said legs, said top member being provided with cross pieces welded to the under side thereof constituting a support on which a receptacle may be placed in an upright position or in 90 an inclined position with its bottom resting against one cross member and its side against the adjacent cross member, and a plurality of triangular horizontal members 95 welded at their angles to said legs and constituting braces therefor, said horizontal members being provided with cross bars disposed in spaced relation to one of the side members thereof constituting a support on which receptacles may be placed in an inclined 100 relation with their bottoms resting against the cross bars and their sides resting against the coacting side member.

2. In a stand, the combination of legs disposed in triangular relation with their 105 angles inwardly, an annular top member

2
welded to the upper ends of said legs, said top member being provided with cross pieces welded to the under side thereof constituting a support, and a plurality of triangular horizontal members welded at their angles to said legs and constituting braces therefor, said horizontal members being provided with cross bars disposed in spaced relation

to one of the side members thereof constituting a support on which receptacles may be placed in an inclined relation with their bottoms resting against the cross bars and their sides resting against the coacting side member. 10

CHARLES H. JARVIS. [L. s.]
